1 Claim

ABSTRACT OF THE DISCLOSURE

A shoe fastener comprising an elastic band disposed between two fastening members which are constructed for insertion into shoe eyelets. The fastening members comprise bases with legs protruding therefrom, each leg having a right angle bend whereby the leg lies flat after insertion into a shoe eyelet.

This invention relates to shoe fasteners.

It is an object of the invention to provide an easily operated shoe fastener of efficient and inexpensive construction.

The invention features a shoe fastener comprising two fastening members and an elastic band disposed between them. The elastic band has an unstretched length less than the distance between opposite eyelets of the shoe on which the fastener is to be used and has loops at its ends. Each fastening member comprises a base to which the band is connected and two legs protruding from the base perpendicular to the axis thereof. The base has a length equal approximately to the separation of successive eyelets on the shoe with which the shoe fastener is to be used. Each of the legs has an approximately right angle bend at a distance from the base approximately equal to the thickness of the shoe leather. The base of each fastening member is inserted into one of the loops of the elastic band.

Other objects, features, and advantages will appear from the following description of a preferred embodiment of the invention, taken together with the attached drawings thereof, in which:

FIG. 1 illustrates a shoe employing shoe fasteners of the invention;

FIG. 2 is a partially broken away perspective view of a shoe fastener according to the invention;

FIG. 2A illustrates the construction of an element of the shoe fastener of FIG. 2; and

FIG. 3 is a section taken at 3—3 of FIG. 1.

FIG. 1 shows shoe fasteners of the invention, indicated generally by 10 and 10', in place in a shoe 12.

As will be more fully described below, each fastener is designed to employ two consecutive eyelets on each collar, 14, of the shoe. Therefore, the four eyelet shoe shown in FIG. 1 requires only two fasteners.

The construction of the shoe fastener is most easily described by reference to FIG. 2. The shoe fastener 10 has an elastic band 16, the ends of which are turned under and stitched to the band thereby forming loops 18 and 20. The loops 18 and 20 are disposed around base por-

2

tions 22 and 24 of fastening members 26 and 28. The base portions 22 and 24 as well as the elastic band 16 have widths approximately equal to the eyelet spacing of the shoe, as shown in FIG. 1. This assures that legs 30 and 32 of fastening member 26 and legs 34 and 36 of fastening member 28 may be inserted conveniently into the eyelets. As illustrated in FIG. 2, the entire fastening member may be constructed as a integral piece of a rigid material. The embodiment illustrated is constructed of heavy metal wire.

The detailed construction of a fastening member is shown in FIG. 2A. In this diagrammatic illustration, a cartesian coordinate system is superimposed upon a fastening member 26. With the base 22 aligned with the X-axis, each leg 30 and 32 meets the base, at an end thereof, in a right angle. Thus, the legs initially lie in the Y-axis direction. Each leg, however, has a right angle bend causing a portion of the leg to lie in the Z-axis direction. With the Y-axis portion of the legs chosen to be approximately equal to the thickness of the leather, this construction provides a fastening member which firmly remains in place while causing no discomfort to the wearer of the shoe, as may be seen by reference to FIG. 3.

The section of FIG. 3 illustrates the shoe fastener in place in a shoe. As therein shown, with the Y-axis portions of the fastening members' legs appropriately sized, the Z-axis portions will lie flat comfortably between the shoe collar 14 and tongue 38.

Other embodiments will occur to those skilled in the art and are within the following claims.

What is claimed is:

1. A shoe fastener comprising two generally L-shaped in longitudinal cross-section fastening members and an elastic band disposed between said fastening members, said band having an unstretched length less than the distance between opposite eyelets of the shoe on which said fastener is to be used, each said fastening member comprising a base to which said band is connected and two legs, said legs having portions thereof protruding from said base perpendicular to the axis thereof and defining with said base a plane, said base having a length equal to the separation of successive eyelets on the shoe with which said shoe fastener is to be used, each of said legs having a right angle bend at a distance from said base approximately equal to the thickness of the shoe leather each of said legs having end portions extending from said bend adapted to lie comfortably between a shoe collar and shoe tongue of an associated shoe.

UNITED STATES PATENT OFFICE
CERTIFICATE OF CORRECTION

Patent No. 3,550,218 Dated December 29, 1970

Inventor(x) Fred Melvin Woolner

It is certified that error appears in the above-identified patent and that said Letters Patent are hereby corrected as shown below:

Column 2, line 8, after "as" change "a" to
--an--;

Column 2, line 20, after "equal to" change
"te" to --the--;

Column 2, line 44, after "distance from said"
insert --base--.

Signed and sealed this 22nd day of June 1971.
